UNITED STATES PATENT OFFICE.

CHESTER J. WELSH, OF CONNEAUT, OHIO.

REENFORCED SPLIT D HANDLE.

Application filed February 13, 1922. Serial No. 536,182.

To all whom it may concern:

Be it known that I, CHESTER J. WELSH, a citizen of the United States, residing at Conneaut, in the county of Ashtabula and State 5 of Ohio, have invented certain new and useful Improvements in Reenforced Split D Handles; and I do hereby declare the following to be a full, clear, and exact description of the same, reference being had to the 10 accompanying drawing forming part of this specification.

This invention relates to handles for shovels, spades and other like implements and more particularly to handles commonly 15 known as split D-handles wherein the upper end portion of the shaft or stem is bifurcated to form two diverging arms between which, at the upper ends thereof, is inserted the grip bar for the hand of the user.

20 An object of the present invention is to reinforce a handle of this type in such manner as to provide the greatest possible protection against injury to the handle, particularly to the arms of the shaft, the reinforcing 25 member constituting the subject matter of this invention being of such construction that the handle will not necessarily be rendered useless even though one of the arms should split.

30 Another object is to provide a reinforcing member that may be secured on the grip bar and arms without materially weakening said arms.

A further object is to permanently secure 35 the grip bar against rotation on the pin by which it is held between the arms.

Other objects of the invention are to provide a reinforcement which is composed of a minimum number of pieces, which is economical 40 to manufacture, and which will rigidly unite the parts of a wooden handle.

In the accompanying drawings—

Figure 1 is an elevational view showing an embodiment of the preferred form of the 45 invention;

Fig. 2 is a sectional view on the line 2—2 of Fig. 1; and

Fig. 3 is a detail view.

The wooden shaft or stem carrying the 50 shovel, spade or other implement, is indicated at 10, its upper end portion being bifurcated forming the two arms 11, 12. The arms 11, 12 diverge upwardly and a cross grip bar 13 is inserted between their upper 55 ends, being held therein by a transverse pin 14 or other suitable fastening means of like

nature, as will be more fully described later. At a point just below the lower end of the bifurcation in the shaft 10, a rivet 15 extending transversely of the bifurcation is 60 provided in the shaft to prevent splitting of the latter.

The arms 11, 12 of the handle are each reinforced or strengthened by a reinforcing member that is preferably made integral 65 from sheet metal. Said reinforcing members each comprise a ferrule or ring portion 16 adapted to encircle the adjacent end portion of grip bar 13, the ends of the grip bar being somewhat reduced in diameter 70 to allow for the thickness of the material from which the reinforcing member is made whereby said rings or ferrules will lie substantially flush with the intermediate portion of the bar and present a smooth sur- 75 face for the hand of the user.

The upper ends of arms 11, 12 are protected by a cap portion 17 formed integrally with the ring portion 16, said cap 17 fitting over and encasing the upper ends of the 80 arms. Extending down from the ring and cap portions 16, 17, are the reinforcing strips proper, said strips, as shown, being in the form of split sleeves 18 practically surrounding the shaft arms 11, 12. Said strips or sleeves 18 extend down on both the inner and outer sides or faces of each arm, the vertical edges 19 of the split in the respective sleeves coming in close proximity to each other on the inner face of the arms.

The several parts described are securely and rigidly held together by a pin 14, or rivet, extending through the grip bar, the arms, and the upper portions of the reinforcing members; and to prevent the grip bar rotating or turning on said pin, the ring portions of the reinforcing members are indented to form inwardly extending prongs 20 that project into the grip bar transversely of the grain of the material from which said bar is 100 made.

The reinforcing members of the present invention possess several advantages attributable directly to their novel construction, namely, the arms are reenforced from both 105 their inner and outer sides or faces; the sleeves practically surround and encase the arms and if an arm should split it has been found that the reinforcing member is sufficient to withstand the strains under which 110 the arm is normally placed; the sleeve extending around on the inner face of the

arm is sufficient to attach the member, at its lower portion, to the arm thus eliminating the necessity of forming a hole through the arm (thus greatly weakening the arm and increasing the liability of its splitting) for the reception of a rivet for securing the reinforcing member to the arm.

What is claimed is:

10 A D-handle comprising a wooden shaft bifurcated adjacent its upper end to form diverging arms, a grip bar inserted between said arms, a reinforcing member for each

arm comprising a ring portion fitting over the adjacent end of the grip bar, a cap enclosing the upper end of the arm and a sleeve-like portion extending down from said cap and ring and substantially surrounding the upper portion of the arm, and a pin passing through the grip bar, arms and reinforcing members, said arms and sleeves being imperforate between said grip bar and the bottom of the bifurcation in the shaft, and said sleeves having a smooth exterior surface.

CHESTER J. WELSH.
